Patented Feb. 10, 1925.

UNITED STATES PATENT OFFICE.

JOSEPH WALTON, OF LOCKWOOD, MISSOURI.

RAILWAY SIGNAL.

Application filed August 10, 1920. Serial No. 402,589.

To all whom it may concern:

Be it known that I, JOSEPH WALTON, a citizen of the United States, residing at Lockwood, in the county of Dade and State 5 of Missouri, have invented a new and useful Railway Signal, of which the following is a specification.

This invention relates to railway signaling devices, and more particularly to an 10 automatic signal adapted to be employed more particularly on bridges or crossings to cause a signal to be made when washouts or fires occur, to warn the engineer of the approaching danger.

15 A further object of the invention is to provide means employed in connection with the usual track relay to cause the operation thereof, when the circuit to the relay becomes broken.

20 With the foregoing and other objects in view which will appear as the description proceeds, the invention resides in the combination and arrangement of parts and in the details of construction hereinafter described 25 and claimed, it being understood that changes in the precise embodiment of the invention herein disclosed, may be made within the scope of what is claimed, without departing from the spirit of the invention.

30 Referring to the drawing:—

Fig. 1 illustrates a plan view of a track section equipped with a signaling device constructed in accordance with the present invention.

35 Fig. 2 is a plan view illustrating in diagrammatic view more clearly the circuit layout.

Referring to the drawing in detail, the reference character 5 designates the rails of a track section, and the reference character 6 designates the rails of the adjacent section, which rails are in circuit with the battery 7 as by means of the wire 8, which is the positive wire of the circuit, the circuit including a wire 9 which has connection with the fusible wire 10 through the connection 11, the wire 10 being disposed in parallel relation with the rails associated therewith, the wire passing under the rail section and 45 rearwardly as at 12, along the supporting ties of the track from where they pass to the negative side of the battery indicated at 13 and through the opposed rail.

A shunt wire indicated at 14 connects the 50 rails of the adjacent track sections, so that

if the track is broken, the circuit will be shunted to cause the operation of the usual track relay indicated at 15, and which is in circuit with the rails 5 as by means of the wires 16 and 17. The rail track sections are 60 insulated from each other as by means of the insulating material 18.

In the operation of the device, assuming that a train is passing over the rail sections, it is obvious that when the wheels of the 65 train pass into a section which is in circuit with the relay, the circuit will be shunted through the wheels to cause the operation relay.

The electric current passes from the battery 7 through the wire 8 where the same connects with the rail section at the opposite side of the track, from where the current is carried to the wire 9, through the rail section and through the wires 12 and 75 to the rail 5' of the track section 5, the rail 5' being in circuit with the wire 17 which in turn is in circuit with the relay 15.

The negative circuit from the battery 7 embodies the wire 13 which connects with 80 the rail 6' of the track section 6 and is carried to the rail 7' of the track section 5 through the wire 14. The rail 7' is in circuit with the wire 16, which in turn is in circuit with the relay 15. It is therefore 85 obvious that the positive rail of one section, has its ends insulated from the negative rail of the adjacent section, and that the negative rail of one section is insulated from the positive rail of the adjacent section. 90

It follows that if a section of the track is washed away, the circuit to the relay 15 will be broken to cause the operation thereof, which in turn operates a switch to a suitable signal not shown, and which is disposed at 95 one side of the track in full view of the operator of a locomotive.

It might be further stated however that the wires 10 and 12 are formed preferably of lead or other fusible material, so that 100 in case of fire, the circuit will be easily fused to cause the operation of the relay.

It might be further stated that the system operates to normally hold the relay energized, and retain the signal controlled by the 105 relay, out of operation, so that should the insulation between adjacent rails become defective, the circuit to the relay 15 will be shunted through the wire 20 to maintain the relay in operation to cause the same to 110

display a signal should the circuit be shorted as by means of a train passing over the rails of a section.

Having thus described the invention, what is claimed as new is:—

1. In combination with a railway block system in which electric currents are carried through the track rails, said track extending across a supporting structure; means insulating the contiguous ends of rails of the track at a point near said supporting structure; and a signal wire adapted to be broken by accident to the structure, which wire is looped across the supporting structure, and has its terminal ends secured to the contiguous ends of the rails on the opposite sides of the insulated joint.
2. A railway block signal system according to claim 1, in combination with a shunt wire connected to the track rails in position.

to operate the signal in the event of defective insulation between said contiguous ends of rails near said supporting structure.

3. A railway block signal in accordance with claim 1, in which the loop wire connects an approach rail on one side of the track with a rail on the structure on the other side of the track, and a shunt wire which connects the approach rail on the latter side of the track with a rail on the structure on the first mentioned side of the track; as and for the purposes described.

In testimony that I claim the foregoing as my own, I have hereto affixed my signature in the presence of two witnesses.

JOSEPH WALTON.
